Asa Ren Lee, Cranford, N. J., assignor to The Thomas & Betts Co., Elizabeth, N. J., a corporation of New Jersey

Application January 9, 1956, Serial No. 39,652

Term of patent 14 years

(Cl. D54—13)

Fig. 1 is a top plan edge view of a combination cutting and crimping tool showing my new design;

Fig. 2 is an elevational view showing one side of the combination cutting and crimping tool; and

Fig. 3 is a similar elevational view showing the opposite side of the combination cutting and crimping tool.

The characteristic features of my design for a combination tool as disclosed reside in the head portions thereof having the configuration and appearance as illustrated.

I claim:

The ornamental design for a combination cutting and crimping tool, as shown and described.
